UNITED STATES PATENT OFFICE,

CHARLES E. RICE AND SAMUEL F. ETTINGER, OF LITTLE ROCK, ARKANSAS,
ASSIGNORS OF ONE-HALF TO ALLEN N. JOHNSON, TRUSTEE, OF SAME
PLACE.

CAR-FENDER.

SPECIFICATION forming part of Letters Patent No. 574,344, dated December 29, 1896.

Application filed March 21, 1896. Serial No. 584,235. (No model.)

To all whom it may concern:

Be it known that we, CHARLES E. RICE and SAMUEL F. ETTINGER, citizens of the United States, and residents of Little Rock, in the 5 county of Pulaski and State of Arkansas, have invented certain new and useful Improvements in Car-Fenders; and we do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a representation of the invention and is a perspective view. Fig. 2 is a vertical longitudinal section, and Fig. 3 is a view in detail of the apron in section.

This invention has for its object the 20 vision of a novel and efficient car-fender; and it consists in the novel construction and combination of the parts thereof, all substantially as hereinafter described, and pointed out in the appended claims.

25 Referring to the accompanying drawings, the letter A designates the forward or platform portion of the car.

B designates the fender-frame, which preferably consists of the parallel lower rods or 30 bars b, one of which is hinged or pivoted to the front end of the car near each side, and which extends downward and forward to points considerably in advance of the car and a short distance above the level of the track- 35 way; also, of the upper parallel rods c, one at each side, which extend obliquely forward and downward to the free-end portions of the rods b, to which they are connected or joined.

The rods c are connected to the car at their 40 upper ends by means of stiff coiled springs C, which are preferably of sufficient strength to normally hold said frame and fender up out of contact with the track and track-bed. Each of said rods c is also preferably formed 45 in two sections, united by a turnbuckle C², by means of which the tension of its connecting-spring may be adjusted.

D D' are two parallel rollers which are journaled transversely between the rods b, the 50 roller D being at the extreme forward end of the frame, while the roller D' is about mid-

way of its length and is consequently considerably above roll D.

55 E is an endless apron which extends around and is carried by these rollers. This apron has preferably a roughened surface to enable it to more readily catch hold of an object struck, as the clothing of a person, and a suitable surface of this character may be provided by forming the body of the apron of 60 leather or of strong fabric, with an upper covering of thin sheet metal upon which the roughened surface is formed, as by punching numerous small holes or indentations therein from the under side outward. We do not, 65 however, wish to limit ourselves to a roughened surface of any particular character, nor, in fact, to the use of a roughened surface at all, since we may use an endless apron of any suitable character.

70 Journalized to the forward end portion of the frame, one upon each side, are two small wheels F, which are designed to run upon the track-rails when the fender is lowered sufficiently to permit this. These wheels have 75 cogs G on their inner faces, which mesh with similar cogs G' on the lower roller D and by means of which the apron is moved. The upper portion or branch of the apron is in 80 this manner, when the wheels F are in engagement with the track, moved upwardly and rearwardly.

H is a platform or basket to the rear of said apron and which may be formed of wire-netting, cordage, or any other suitable material. 85 In the drawings we have shown lateral guards for the basket and apron; but these may be omitted.

When the forward end of the fender strikes 90 and trips an object, the object is thrown onto the apron, and its weight brings the wheels F into engagement with the track-rails, causing said apron to revolve and carry the object back onto the platform or basket H. If preferred, however, these wheels may be kept in 95 contact with the track all the time and the apron kept in constant motion. Instead of providing these wheels F with cogs for the purpose of driving the roller D it is obvious that

100 said roller or the roller D' may be driven by means of a suitable connection with one of the axles of the car.

Having thus described our invention, what we claim as new, and desire to secure by Letters Patent, is—

1. A car-fender having a pick-up consisting of an endless rearwardly-moving apron having a body portion of strong fabric and an upper covering of sheet metal having numerous points or projections struck upwardly therefrom, and carrying and driving rollers 10 for said apron, substantially as specified.

2. The car-fender having the frame composed of the lower inclined rods *b* hinged or pivoted to the car, the upper inclined rods *c*, whose lower forward ends are connected to 15 the lower forward ends of the rods *b*, said rods *c* being made in two sections adjustably

connected, the springs connecting said rods *c* to the car, the upwardly and rearwardly inclined apron at the forward portion of said frame, the carrying-rollers for said apron 20 journaled in said frame the track-wheels geared to one of the carrying-rollers of the said apron, and the basket or receiver to the rear of said apron, substantially as specified.

In testimony whereof we affix our signatures in presence of two witnesses.

CHAS. E. RICE.
SAMUEL F. ETTINGER.
